Primary Examiner — Jennifer L Rempfer*Assistant Examiner* — Elizabeth Anne Glassberg(57) **CLAIM**

The ornamental design for a combined dog harness and pouch, as shown and described.

DESCRIPTION

FIG. 1 is a perspective view of a combined dog harness and pouch, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict portions of the combined dog harness and pouch that form no part of the claimed design.

1 Claim, 4 Drawing Sheets(56)
